UNITED STATES PATENT OFFICE.

CHARLES F. HOPEWELL, OF CAMBRIDGE, MASSACHUSETTS, ASSIGNOR
TO UNI SIGNAL COMPANY, A CORPORATION OF MAINE.

ELECTRIC SWITCH.

SPECIFICATION forming part of Letters Patent No. 757,925, dated April 19, 1904.

Application filed October 7, 1903. Serial No. 176,021. (No model.)

To all whom it may concern:

Be it known that I, CHARLES F. HOPEWELL, of Cambridge, county of Middlesex, State of Massachusetts, have invented an Improvement 5 in Electric Switches, of which the following description, in connection with the accompanying drawings, is a specification, like characters on the drawings representing like parts.

This invention relates to an electric switch 10 which is especially designed for use in connection with trolley signaling apparatus employed for electric street-railways. The switch is designed to operate a circuit leading from the trolley-wire or other current-carrying wire to a ground or other return which includes the operating-electromagnet of the trolley signaling mechanism, and said switch is designed to be operated by a trolley or equivalent device passing along the wire. 15 The invention has for its object to construct 20 a switch whereby the movable contact member of a circuit-controlling device, which device may be a circuit-closer, shall be moved into a position to close the circuit by a suitable operating device which is constructed 25 and arranged to not only positively move said contact member to close the circuit, but also to positively hold said member in its abnormal position with the circuit closed during 30 the time said operating device is returning to its normal position, said contact member resuming its normal position just as or about the time said operating device resumes its normal position; also, to provide a suitable retard- 35 ing device for the operating device which is adapted to be brought into action on the return movement only of said operating device, whereby the time required for the operating device to resume its normal position is mate- 40 rially increased; also, to provide a locking device which positively holds the movable contact member of the circuit-controlling device in its abnormal position with the circuit closed while the operating device is resuming its 45 normal position, the position of said locking device being controlled by said operating device; also, to provide the operating device with means for positively moving the locking device into locking position in case it should fail

to properly operate as intended; also, to provide means for giving to the operating device an initial movement of, say, thirty degrees and thereafter giving to it a subsequent movement of, say, sixty degrees in continuation of said initial movement to thereby augment the movement of the operating device for purposes to be hereinafter explained; also, to so construct and arrange the parts that when two circuit-closers are provided, as is usually the case, many of the parts may be common to both to thereby simplify the construction.

Figure 1 shows in side elevation an electric switch embodying this invention. Fig. 2 is a horizontal section of the electric switch shown in Fig. 1, taken on the dotted line 2 2. 65 Fig. 3 is a side elevation of the switch, showing the actuator and one of the circuit-controlling devices and the switch-operating mechanism therefor. Fig. 4 is a vertical section of the switch shown in Fig. 1, taken on 70 the dotted line 4 4. Fig. 5 is a detail showing the operating device for the movable contact member and the retarding device for said operating device.

The switch will first be described as having 75 a single circuit-controlling device and operating mechanism therefor.

a represents a frame or housing adapted to be secured to a suitable support above the trolley-wire, said frame being constructed and 80 arranged to support the switch and its operating mechanism, with the actuator in position to be engaged and operated by a trolley, although if the device is to be used in connection with what is commonly called a "third-rail" system the frame will necessarily be differently constructed, so as to hold the actuator in position to be engaged by the shoe. So far as my invention is concerned the switch is adapted for either purpose, and hence herein in the word "trolley" is intended to include 85 its equivalent device when used in connection with a third-rail system.

b represents the stationary contact member of the circuit-controlling device, which is here- 95 in shown as a flat spring-acting strip or pen attached to the frame, and *b'* is the movable contact member of said circuit-controlling de-

vice, which is herein shown as an arm secured to a pivot-rod b^2 and made of suitable length and so disposed that its upper end is movable into and out of engagement with the member 5 b . A weighted arm b^3 is also secured to said pivot-rod b^2 , which normally rests upon a stop b^4 and holds the movable contact member out of engagement with the stationary contact member.

10 A projection b^5 is formed on an arm secured to the pivot-rod b^2 , which occupies a position beneath one edge of a cam-plate c . The cam-plate c constitutes the operating device for the circuit-controlling device, and said cam-plate is loosely mounted on a rod or bar c' 15 and is designed to be reciprocated through an arc of ninety degrees or thereabouts. To give the cam-plate c a quarter-turn in one direction, said plate has formed on it a projection c^2 , which extends downwardly and normally occupies a position at one side of an upward extension d on the actuator d' , which is pivoted at d^2 and which is made as a bifurcated plate to straddle the trolley-wire, so as 20 to be engaged by a passing trolley and moved by said trolley on its pivot. As the actuator d' is moved in a direction toward the right, as it will be by the trolley passing in the direction of the arrow, Fig. 3, the extension d will engage the projection c^2 on the cam-plate c and turn said plate on its axis a short distance, and the projecting portion or edge of said plate which overlies the projection b^5 will 25 engage said projection and move the contact member b' toward and into engagement with the contact member b . It may be stated that the movement thus given to the cam-plate by the extension d is approximately thirty degrees, and this movement is herein referred 30 to as the "initial" movement. Further movement is given to the said cam-plate c in continuation of said initial movement by means of a link f , one end of which is loosely connected to the upper end of the extension d 35 and the other end of which is slotted, as at f' , and engages a pin f^2 , projecting laterally from the cam-plate. Normally the pin f^2 occupies a position substantially midway the length of the slot, so that the actuator d' is free to move 40 a short distance while its extension d engages and moves the cam-plate, during which time the link moves longitudinally independent of the cam-plate; but as soon as the outer end of the slotted portion strikes the pin f^2 45 then as the actuator continues to move in the direction toward the right the link will pull upon the cam-plate and turn said plate on its axis in the same direction that it is being moved by the extension d , and such further movement of the cam-plate is approximately 50 sixty degrees. During this subsequent movement of the cam-plate the portion thereof which engages the projection b^5 rides along on said projection and does not act to further 55 move the contact member b' . Thus a quarter-

turn is given to the cam-plate by two successive movements, one in continuation of the other. If the projection c^2 on the cam-plate is omitted, the cam-plate will be moved by the link and the contact member b' moved. Hence 70 I do not desire to limit my invention to the employment of both movements. I prefer to provide the initial movement in order that the actuator may be struck a sudden blow without injuring the parts, and I provide the 75 subsequent movement in order that the retarding device (to be described) may be engaged in such a manner that it shall retard the return movement of the cam-plate for a longer period of time than if said subsequent 80 movement was not provided.

As the cam-plate is given a quarter-turn and the movable contact member moved into engagement with the stationary contact member the projection b^5 remains in continuous 85 engagement with the cam-plate, so that said cam-plate positively holds said contact member in its abnormal position with the circuit closed.

By so locating the slotted portion of the 90 link that the pin f^2 normally occupies a position substantially midway the length of the slot it will be seen that the actuator d' may be swung in a direction toward the left from a perpendicular and the link moved up a short 95 distance and then turned on the pin f^2 as a pivot as the pivotal connection of the link, with the extension d on the actuator, passes a straight line extending from the pivot d^2 of the actuator to the pin f^2 , and then said link 100 will be drawn down as the actuator continues to move toward the left. Thus a movement of the actuator in a direction toward the left from a perpendicular will not move the cam-plate c . 105

A locking device is provided for locking the movable contact member b' when in engagement with the stationary contact member b , and, as herein shown, said locking device consists of a short arm g , pivoted at g' to the 110 frame and having on its lower edge a projection g^2 , which is adapted to engage an arm b^6 , projecting from the movable contact member. The locking-arm g is normally held up in a plane out of the path of movement of said arm b^6 by the portion c^3 of the cam-plate, being held pressed into engagement with said cam-plate by a spring, although said spring may be omitted, and as the cam-plate is turned by the actuator said portion c^3 descends, and the locking-arm, which rests upon it, follows 115 and is thereby brought into the path of movement of the arm b^6 . The position of the locking-arm is thus controlled by the cam-plate, and said arm will be moved at the same time 120 that the contact member b' is moved, and consequently will be brought into position to be engaged by the arm b^6 at the proper time. As the cam-plate is given a quarter-turn by the actuator the locking-arm continues to 125 130

bear upon it, and the end of said arm enters a recess c^4 , formed in said cam-plate, and by bottoming in said recess serves as a stop for the cam-plate. As the locking-arm bears upon 5 the cam-plate, it will be seen that as the cam-plate returns to its normal position the locking-arm will be raised and the arm b^6 thereby disengaged, and as soon as said arm b^6 is disengaged the movable contact member will 10 be returned to its normal position by the weight b^3 .

In case the locking-arm should not properly respond as the cam-plate moves the projecting portion c^{20} on the cam-plate, which forms 15 one side of the recess c^4 , will be brought into position to overlie and engage said arm, and thereby positively move it. While I prefer to employ a locking device for the movable contact member which holds it while the cam-plate is returning to its normal position, yet 20 as said plate is constructed to positively hold said contact member with the circuit closed for approximately the entire return movement of the plate said locking device may be 25 omitted. The locking device, however, holds the contact member until the cam-plate has nearly resumed its normal position, when it is operated and said contact member suddenly released, which is a very desirable function. 30

A spring of any suitable description, herein represented as a spiral spring h , is connected at one end to the cam-plate and at the opposite end to the frame, which serves to restore 35 the cam-plate to its normal position.

In order that the cam-plate may return to its normal position slowly, so that the circuit-controlling device will remain closed for a period of long duration, a retarding device is 40 provided for said cam-plate. As a retarding device for the cam-plate an escape-wheel i is mounted loosely on the shaft c' , and a pallet i' is provided which cooperates with it, and on one side of said escape-wheel a ratchet-wheel i^2 is secured which turns with the escape-wheel, and a pawl i^3 is provided adapted to engage said ratchet-wheel i^2 , which is pivoted at i^4 to the cam-plate and which is normally held out of engagement with the ratchet-wheel by an extension i^5 , formed on said pawl engaging the frame at 50 when the cam-plate is in its normal position; but when the cam-plate is moved a short distance the extension i^5 on the pawl will be removed from 55 engagement with the frame, and the pawl will then be moved into engagement with the ratchet-wheel by means of a spring i^7 , the free end of which bears upon the pawl and the opposite end of which is attached to the cam-plate. The teeth of the ratchet-wheel are directed toward the right, so that as the cam-plate is given a quarter-turn in a direction toward the right the pawl will slip freely 60 over the teeth of the ratchet-wheel; but as 65 the cam-plate returns to its normal position

said pawl will engage the teeth of the ratchet-wheel and the ratchet-wheel will be turned and the escape-wheel correspondingly rotated. Thus the cam-plate will be retarded during its return movement. 70

The switch thus far described comprises a single circuit-controlling device, an operating device therefor, a locking device for the circuit-controlling device, a retarding device for the operating device, and an actuator for said operating device; but ordinarily the switch will comprise two circuit-controlling devices, a locking device for each circuit-controlling device, and an operating device for each circuit-controlling device, although the same retarding device and the same actuator will be employed for both operating devices. 75

The second circuit-controlling device is made like the circuit-controlling device above described and comprises, essentially, a stationary contact member j and a movable contact member j' . 80

k represents the cam-plate, which serves as the operating device, which is made like the cam-plate c . 90

m represents the slotted link, which connects said cam-plate with an extension d on the actuator d' . 95

n represents the ratchet-wheel, which is secured to the opposite side of the escape-wheel i . 95

o represents the pawl, which is adapted to engage said ratchet-wheel, and p the spring, which is attached to the cam-plate and serves to restore it. The operating device or cam-plate k is operated by the actuator d' , moving 100 in a direction toward the left, and the operation of said plate and other parts is the same as above described.

Having thus described my invention, what I claim as new, and desire to secure by Letters 105 Patent, is—

1. In an electric switch, the combination of a circuit-controlling device, an operating device therefor, an actuator for said operating device for giving it an initial movement, and a slotted link connecting said actuator with said operating device for giving said operating device a subsequent movement in continuation of said initial movement, and a frame supporting the parts with the actuator in position 110 to be engaged by a trolley, substantially as described. 115

2. In an electric switch, the combination of a circuit-controlling device, a cam-plate for operating it, an actuator adapted to be operated by a trolley having an extension which, when the actuator is moved in one direction only, engages a projection on the cam-plate for giving said plate an initial movement, a slotted link connected at one end to said extension on the actuator, and at the opposite end to said cam-plate for giving said cam-plate a subsequent movement in continuation of said initial movement, substantially as described. 125

3. In an electric switch, the combination of 130

a circuit-controlling device, comprising a stationary contact member, and a movable contact member, the latter having a cam-engaging projection, a cam-plate for engaging said projection to move the movable contact member into engagement with the stationary contact member, and for holding it in such position while the cam-plate occupies its abnormal position, an actuator for said cam-plate, a retarding device for said cam-plate, means for engaging said retarding device on the return movement of said cam-plate and a frame supporting the parts with the actuator in position to be engaged by a trolley, substantially as described.

4. In an electric switch, the combination of a circuit-controlling device comprising a stationary contact member and a movable contact member, the latter having a weighted arm and also having a cam-engaging projection, a stop upon which said weighted arm rests, a cam-plate for engaging said projection to move the movable contact member into engagement with the stationary contact member and for holding said member in such a position while the cam-plate occupies its abnormal position, an actuator for said cam-plate, a retarding device for said cam-plate, means for engaging said retarding device on the return movement of said cam-plate and a frame supporting the parts with the actuator in position to be engaged by a trolley, substantially as described.

5. In an electric switch, the combination of a circuit-controlling device comprising a stationary contact member, and a movable contact member, a locking device for holding said movable contact member in engagement with the stationary contact member, an operating device for said contact member, which moves it into engagement with the stationary contact member and also into engagement with the locking device, an actuator for said operating device, and a frame supporting the parts with the actuator in position to be engaged by a trolley, substantially as described.

6. In an electric switch, the combination of a circuit-controlling device comprising a stationary contact member and a movable contact member, a locking-arm for locking said movable contact member in engagement with said stationary contact member, an operating device for said contact member which governs the position of said locking-arm, an actuator for said operating device, and a frame supporting the parts with said actuator in position to be engaged by a trolley, substantially as described.

7. In an electric switch, the combination of a circuit-controlling device comprising a stationary contact member and a movable contact member, a locking-arm for locking said movable contact member in engagement with said stationary contact member, a cam-plate on which said locking-arm bears which gov-

erns its position, a projection on said movable contact member adapted to be engaged by said cam-plate, an actuator for said cam-plate, and a frame supporting the parts with the actuator in position to be engaged by a trolley, substantially as described.

8. In an electric switch, the combination of a circuit-controlling device, an operating device therefor, an actuator for said operating device, a locking-arm for the movable contact member of said circuit-controlling device, the position of which is governed by said operating device, an engaging portion on said operating device which strikes against the end of said locking-arm and limits its movement, substantially as described.

9. In an electric switch, the combination of a circuit-controlling device, an operating device therefor, an actuator for said operating device, a locking-arm for the movable contact member of said circuit-controlling device, the position of which is governed by said operating device, and a projection on said operating device which is adapted to engage said locking-arm, substantially as described.

10. In an electric switch, the combination of a circuit-controlling device comprising a stationary contact member and a movable contact member, a projection on said movable contact member, a cam-plate which engages said projection and moves said contact member into engagement with the stationary contact member, and holds it in such position, a pivoted actuator adapted to be operated by a trolley, and a slotted link connecting said cam-plate with said actuator, substantially as described.

11. In an electric switch, a circuit-controlling device, an operating device therefor, an actuator, a slotted link connecting said operating device with said actuator, a retarding device for said operating device, and means for engaging said retarding device on the return movement of said operating device, substantially as described.

12. In an electric switch, the combination of a circuit-controlling device, an operating device therefor, an actuator for giving to said operating device an initial movement, and a slotted link connecting said actuator with said operating device for giving to it a subsequent movement in continuation of said initial movement, a retarding device for said operating device, and means for engaging said retarding device on the return movement of said operating device, substantially as described.

13. In an electric switch, a circuit-controlling device, an operating device therefor, an actuator for giving to said operating device an initial movement, and a slotted link connecting said actuator with said operating device for giving to it a subsequent movement in continuation of said initial movement, a pawl borne by said operating device, a ratchet-wheel which it engages, an escape-wheel to

which said ratchet-wheel is secured, and a pallet for said escape-wheel, substantially as described.

14. In an electric switch, the combination of two circuit-controlling devices, each comprising a stationary contact member and a movable contact member, a cam-engaging projection on each movable contact member, a cam-plate for engaging each projection to move the movable contact member into engagement with the stationary contact member and for holding it in such position while the cam-plate occupies its abnormal position, an actuator for each cam-plate, a retarding device common to both cam-plates, and means for engaging said retarding device on the return movement of the cam-plates, substantially as described.

15. In an electric switch, the combination of two circuit-controlling devices, each comprising a stationary contact member and a movable contact member, an operating device for each movable contact member, a pivoted actuator, a slotted link connecting each operating device with an extension on the actuator and a frame for supporting the parts with the actuator in position to be engaged by a trolley, substantially as described.

16. In an electric switch, the combination of two circuit-controlling devices, each comprising a stationary contact member and a movable contact member, a cam-plate for each movable contact member, a pivoted actuator, a slotted link connecting each cam-plate with an extension on the actuator, and a frame for supporting the parts with the actuator in position to be engaged by a trolley, substantially as described.

17. In an electric switch, the combination of two circuit-controlling devices, each comprising a stationary contact member and a movable contact member, an operating device for each movable contact member, an actuator having two extensions for respectively engaging the operating devices and for giving them an initial movement, a slotted link connecting each operating device with an extension on the actuator for giving to said operating device a

subsequent movement in continuation of said initial movement, and a frame for supporting the parts with the actuator in position to be engaged by a trolley, substantially as described.

18. In an electric switch, the combination of two circuit-controlling devices, each comprising a stationary contact member and a movable contact member, a locking device for each movable contact member, an operating device for each movable contact member which controls the position of the locking device therefor, an actuator for both the operating devices, a slotted link connecting each operating device with an extension on said actuator, and a frame for supporting the parts with the actuator in position to be engaged by a trolley, substantially as described.

19. In an electric switch, the combination of two circuit-controlling devices, each comprising a stationary contact member and a movable contact member, a locking-arm for each movable contact member, a cam-plate for each movable contact member which also controls the position of the locking-arm for said member, an actuator, a slotted link connecting each cam-plate with an extension on said actuator, and a frame for supporting the parts with the actuator in position to be engaged by a trolley, substantially as described.

20. In an electric switch, the combination of two circuit-controlling devices, each comprising a stationary contact member and a movable contact member, an operating device for each movable contact member, an actuator for said operating devices, a slotted link connecting each operating device with an extension on said actuator, a retarding device common to both operating devices, and means for engaging said retarding devices on the return movement of the operating devices, substantially as described.

In testimony whereof I have signed my name to this specification in the presence of two subscribing witnesses.

CHARLES F. HOPEWELL.
